DESIGN FOR A POWDER PUFF CONTAINER
OR THE LIKE

Bernard Ulvad, Leominster, Mass., assignor, by
mesne assignments, to Foster Grant Co., Inc.,
Leominster, Mass., a corporation of Massachu-
sets

Application August 20, 1948, Serial No. 148,204

Term of patent 14 years

(Cl. D86—10)

To all whom it may concern:

Be it known that I, Bernard Ulvad, a citizen
of the United States, residing at Leominster, in
the county of Worcester, State of Massachusetts,
have invented a new, original, and ornamental
Design for a Powder Puff Container or the like,
of which the following is a specification, reference
being had to the accompanying drawing, forming
part thereof, in which:

Figure 1 is an expanded view in elevation of a
powder puff container, embodying the design;

Figure 2 is a top plan view of the powder puff
container;

Figure 3 is a bottom plan view of the powder
puff container; and

Figure 4 is a bottom plan view of the cover of
the powder puff container.

I claim:

The ornamental design for a powder puff con-
tainer or the like, substantially as shown.

BERNARD ULVAD.
